UNITED STATES PATENT OFFICE.

CHARLES MARTIN BAGSHAW, OF LEICESTER, ENGLAND, ASSIGNOR TO GIMSON & CO. (LEICESTER) LIMITED, OF LEICESTER, ENGLAND, A CORPORATION OF GREAT BRITAIN.

LASTING-MACHINE.

1,318,827.

Specification of Letters Patent.

Patented Oct. 14, 1919.

Application filed April 8, 1918. Serial No. 227,195.

To all whom it may concern:

Be it known that I, CHARLES MARTIN BAGSHAW, a subject of the King of Great Britain, residing at 3 St. Saviour's Hill, Leicester, England, have invented an Improvement 5 in or Relating to Lasting-Machines, of which the following is a specification.

This invention relates to lasting machines and concerns those provided with mechanism for cutting or slitting the edges of the 10 upper material as for instance the machine described in British Specification No. 5966 of 1901.

The present invention comprises an improvement 15 in connection with the mechanism for advancing and retracting the cutters, and while it is mainly applicable to mechanism of the character described in the aforesaid specification it is not necessarily 20 to be regarded as being limited in this direction as it may be found to admit of application in other machine mechanism of similar character.

In the machine described in the aforesaid 25 specification, a suitably actuated rack-bar meshes with a rack-pinion which, in turn, intermeshes with a rack-slide adapted for endwise movement in the frame. A cutter-carrying bar has connection with the rack-slide 30 to be moved endwise therewith and a spring is combined with the rack-pinion and operates normally for holding the cutter-carrying bar in the retracted position.

A downward movement imparted to the 35 rack-bar effects, through the medium of the rack-pinion and rack-slide, an advancement of the cutter carrying bar, while an upward movement of the rack-bar causes the cutter-carrying bar to be retracted.

40 The rack pinion is in the form of a double segment having two sets of teeth at different radii, one set of teeth meshing with the rack-bar, while the other set of teeth mesh with the rack-slide. The normal position 45 of the cutter-carrying bar is determined by the contact of one end of the larger segment with a shoulder or fixed abutment on the frame.

It is found that the shock caused by the 50 contact of the end of the segment with the fixed shoulder or abutment is liable to cause breakage of the teeth of the inter-meshing working parts as the arrest of the movement when the cutter-carrying bar is retracted is 55 very sudden.

The present invention has for its object to obviate or reduce the aforesaid shock and to this end consists in providing a cushioning or yielding device or means, which while serving to arrest the return movement 60 of the parts and determine the normal position of same, will, by slightly yielding, obviate the excessive shock or so considerably reduce the concussion as to obviate the 65 breakage of the teeth.

The device is preferably spring controlled and replaces the fixed shoulder or abutment so that upon the end of the segment making contact therewith it will yield and act in the manner of a spring buffer.

In further describing the invention reference will be made to the accompanying drawing wherein a device of convenient form and constituting an example of the invention applied to the machine of the aforesaid 75 specification is illustrated.

In the drawing:—

Figure 1 is a sectional side elevation of the part of the machine concerned by the present invention and shows the cushioning 80 or yielding device applied thereto.

Fig. 2 is a perspective front view of the said cushioning or yielding device.

Fig. 3 is a perspective view of the arresting member of said device *per se*.

Fig. 4 is a detail perspective view of the cutter bars and their operating mechanism.

Like parts are designated by the same reference characters in the several figures of the drawing, and those parts of the machine of the aforesaid specification which are shown in the present drawing, and hereinafter referred to are indicated by the same reference characters as those employed in the said prior specification.

As previously mentioned, the present invention is concerned with the mechanism in a lasting machine for advancing and retracting the slitting cutters.

In the machine, part of which is shown in Figs. 1 and 4 of the present drawing, this mechanism comprises a rack-bar 44 capable of vertical sliding movement a rack-pinion 52 having one set of teeth engaging with the teeth on the rack-bar and another set of teeth arranged in mesh with the teeth on the rack-slide 54, and a spring 76. The cutter 62 is carried on a bar 58 having connection with the rack-slide 54. The spring 76 operates normally for holding the pinion 52

in position with the slide 54, and consequently the cutter 62 retracted, the bar 44 being then uplifted. Upon downward movement being imparted to the rack-bar 44 by 5 the means described in the aforesaid specification, the rack-pinion 52 is caused to turn in the direction indicated by the arrow (Fig. 1), thereby imparting endwise movement to the rack-slide 54 in the frame 56 and advancing the cutter 62. Movement of 10 the parts referred to in an opposite direction for the purpose of retracting the cutter-carrying bar 58 and cutter 62 has been arrested by the contact of the end 52^a of the 15 segment 52^b, with a shoulder or fixed abutment, but according to the present improvement a yielding member is provided to constitute a stop for the same purpose.

In the embodiment shown the yielding arresting device is in the form of a rocker 20 *a* mounted on a pin or screw *b* and having its end *c* suitably shaped to occupy a position over the end 52^a of the segment 52^b. This rocker is controlled by a slidable spring 25 actuated plunger pin *d* furnished with a flat head *e* which presses upon a flat face *f* on a rocker *a*. The arrangement is such that the rocker when turned upon its pin *b* moves the plunger pin *d* in its housing *g* against the action of the controlling spring *h*. Upon the end 52^a of the segment 52^b making contact with the end *c* of the rocker *a*, the latter can, if necessary, yield under the force 30 of the blow by turning on its pin *b* and so act in the manner of a cushion, the spring controlled plunger *d* serving to allow the necessary yield and return the rocker to the normal position afterward.

As described in the specification before referred to, the machine is equipped with 40 two cutter-carrying bars each having mechanism such as already described herein for advancing and retracting same.

The relative arrangement of the bars and 45 their operating mechanisms is shown in Fig. 4, in which the second bar 64, carrying a cutter 66, is shown as operated by the rack bar 50, through the rack pinion 72 and rack slide 70.

Conveniently the same rocker *a* of the 50 device shown in the present drawing serves to constitute the yielding stop for the segment of each cutter-carrying bar, for which purpose its opposite ends *c* and *i* are formed as shown in Figs. 2 and 3 to extend one 55 over each segment 52^b and 72^b (Fig. 4), the rocker moving in either one direction or the other according to which segment end engages the same.

The rocker *a* is mounted by its screw 60 *b* (Figs. 1 and 2) upon the cover plate *j* of the frame 56 said plate and frame being cut away as shown at *k* at each side for the passage and movement of the shaped ends *c* and *i* of the rocker *a*.

The housing *g* of the plunger pin *d* is attached to the cover plate *j* by screws *l*.

The invention is not to be confined to the particular form of yielding arresting device hereinbefore described as it will be obvious 70 that a buffer of other form might effectively be employed to obviate shock. For instance, the segment may make contact with a spring pressed sliding pin or plunger. The details of construction may also be varied 75 without departing from the scope of the invention defined by the appended claims.

What I claim then is:

1. In a lasting machine, the combination 80 with means for cutting or slitting the edges of the work including a cutter and mechanism for advancing and retracting the same, of cushioning means constructed and arranged to arrest the retracting movement of said mechanism, to obviate or reduce 85 concussion for the purpose described.

2. In a lasting machine, the combination 90 with means for cutting or slitting the edges of the work including a cutter and mechanism for advancing and retracting the same, of a spring controlled member arranged to constitute a stop for a part of the retracting mechanism and upon contact of 95 said part therewith to move against the action of its controlling spring to absorb the shock of the arrest.

3. In a lasting machine, the combination 100 with means for cutting or slitting the edges of the work including a cutter and mechanism for advancing and retracting the same, of a pivotally mounted rocker bar having its end formed to constitute an arresting abutment for a part of the retracting mechanism, a flat face on said rocker bar, and a 105 spring actuated plunger pin bearing upon said flat face, for the purpose described.

4. In a lasting machine, the combination 110 with means for cutting or slitting the edges of the work including a cutter and mechanism for advancing and retracting the same, of a pivotally mounted rocker bar having its end formed to constitute an arresting abutment for a part of the retracting mechanism, a flat face on said rocker bar, a housing, a plunger pin slidable within said 115 housing, and bearing upon the face on the rocker bar, and a spring in said housing to actuate the plunger pin, for the purpose described.

5. In a lasting machine, the combination 120 with means for cutting or slitting the edges of the work including a pair of cutters and mechanism for advancing and retracting each cutter, of a spring controlled member arranged to constitute a stop for a part of the retracting mechanism of each cutter and upon contact of said part therewith to act as a cushion and absorb the shock of the arrest.

6. In a lasting machine, the combination 130

with means for cutting or slitting the edges of the work including a pair of cutters and mechanism for advancing and retracting each cutter, of a pivotally mounted rocker bar, and spring actuated means to control the movements of said rocker bar, and an abutment on each end of said rocker-bar, said abutments constituting stops for a part of the retracting mechanism of the respective cutters for the purpose of arresting the movement of same without shock.

7. In a lasting machine, the combination with means for cutting or slitting the edges of the work including a pair of cutters and mechanism for advancing and retracting each cutter, a pivotally mounted rocker bar, arresting abutments on opposite ends of said rocker bar adapted for the contact of a part of the retracting mechanism of the respective cutters therewith, a flat face on said rocker bar, and a spring actuated plunger pin bearing upon said face to control the movements of said bar in both directions, for the purpose described.

8. In a lasting machine the combination with means for cutting or slitting the edges of the work including a pair of rack-slides, a rack-pinion for each rack-slide, a rack-bar for actuating each rack-pinion to advance the rack-slide, and a spring to actuate each rack pinion to retract the rack-slide, of a pivotally mounted rocker-bar, an abutment

on each end of same to constitute an arresting stop for the respective rack-pinion, and a spring actuated device to control the movements of the rocker bar and enable it to yieldingly arrest the retracting movement of either of the rack-pinions, substantially as described.

9. In a lasting machine, in combination, 40 a pair of cutters, a carrying-bar for each cutter, a rack-slide for each carrying-bar, a rack-pinion for each rack-slide, a rack-bar to actuate each rack-pinion in one direction to advance the respective rack-slide, carrying-bar and cutter, a spring to actuate each rack-pinion in the opposite direction to retract said parts, a pivotally mounted rocker bar, an abutment on each end of said rocker bar adapted to be engaged by the respective 50 rack-pinions, a flat face on said rocker-bar, a housing, a plunger pin slidable within said housing, a flat head on said plunger pin bearing upon the flat face of the rocker bar, and a spring in said housing acting upon the 55 plunger pin whereby the rocker bar is capable of a controlled yielding movement to arrest the retracting movement of either rack-pinion, substantially as and for the purpose described.

In testimony whereof, I have signed my name to this specification.

CHARLES MARTIN BAGSHAW.
